COVER FOR TELEPHONE HAND SET

James L. Hvale, River Forest, Ill., assignor to Swiss Harmony, Inc., Chicago, Ill., a corporation of Illinois

Filed May 23, 1967, Ser. No. 7,236

Term of patent 3½ years

(Cl. D26—14)

FIG. 1 is a top plan view of a cover for telephone hand set embodying my new design;

FIG. 2 is a side elevational view of the same, and

FIG. 3 is a cross-sectional view taken substantially along line 3—3 of FIG. 1.

The dominant features of my design reside in the portions shown in full lines.

I claim:

The ornamental design for a cover for telephone hand set, as shown and described.
